DRAFTING MACHINE

Arvid Heireth, Bergenfield, N. J., assignor to
 Keuffel & Esser Company, Hoboken, N. J., a
 corporation of New Jersey

Application June 4, 1941, Serial No. 396,493

21 Claims. (Cl. 33—79)

This invention relates generally to parallel motion drafting devices of the kind in which the several tools which the draftsman handles most frequently are embodied, in principle, in one unit to obviate the necessity of a draftsman reaching about for a required tool and thereby enabling the draftsman to keep his attention concentrated directly upon the drawings. Drafting devices of this character are common in which adjacent ends of two arms usually of equal length are pivoted together, the free end of one arm being secured to a remote portion of a drafting board while the free end of the other arm is provided with a head comprising a protractor and straight-edges which are fixed in angular relation with respect to one another to move about the center of the protractor as an axis. The straight-edges are usually made of box wood or Celluloid and easily become damaged if brought into contact with a hard surface or edge.

Ordinarily, the end of the arm is secured to the drafting board by means of an anchor, so-called, with which the straight-edges at the free end of the articulated arm sometimes come into contact, with consequent damage to the straight-edges so that straight lines may no longer be drawn therewith.

The primary object of the present invention is to prevent damage to the straight-edges and other drawing tools when brought into contact with the anchor. To this end, it is proposed to cushion or shield the straight-edges from the anchor by means of suitable yielding or soft material interposed between the anchor and the straight-edges and which will prevent damage to the straight-edges if brought into contact therewith. In carrying the invention into effect, in one of its aspects, the shielding devices may take the form either of yielding or resilient non-metallic material which will yield upon contact with the straight-edges and is sufficiently soft not to abrade or otherwise damage the straight-edges. In another aspect of the invention, yielding or resilient metallic material is interposed between the straight-edges and the relatively hard and unyielding anchor which yielding or resilient material, when engaged by the straight-edges, will yield so as not to damage the straight-edges.

The invention also has for an object practical and effective devices usually, although not necessarily of metal, by which the cushioning material may be retained in position against displacement.

The invention also seeks shielding devices of the character described which are practical from the standpoint of ease and simplicity of manufacture and durability and practicability in use.

These and other objects of the invention and the means for their attainment will be more apparent from the following detailed description,

taken in connection with the accompanying drawings illustrating various embodiments by which the invention may be realized and in which:

5 Figure 1 is a view, in plan, showing one form of anchor to which the shielding devices of this invention are applied;

10 Figure 2 is a fragmentary view of the anchor in front elevation looking from the line 2—2 of Figure 1 in the direction of the arrows;

Figure 3 is a fragmentary view showing the anchor in side elevation looking from the line 3—3 of Figure 1 in the direction of the arrows, the table being in elevation;

15 Figure 4 is a transverse sectional view of that portion of the anchor overlying the table taken in the plane indicated by the line 4—4 of Figure 1 and looking in the direction of the arrows, the table being omitted in the interest of simplicity of illustration;

20 Figure 5 is a longitudinal view taken in the plane indicated by the line 5—5 of Figure 2 and looking in the direction of the arrows, parts of the anchor being broken away;

25 Figure 6 is a view showing that portion of the anchor overlying the table, as if looking from below in Figure 1 and showing particularly the removable cushioning device of this modification;

30 Figure 7 is a plan view showing another modification of the invention applicable particularly to other forms of anchor, parts being broken away to show details of construction and the straight-edge of the drafting machine used in drawing so-called vertical lines being indicated in broken lines in three positions;

35 Figure 8 is a vertical sectional view taken in the plane indicated by the broken line 8—8 of Figure 7, looking in the direction of the arrows, the table being shown in section;

40 Figure 9 is a fragmentary view looking from above and showing a further form taken by the invention;

45 Figure 10 is a transverse vertical sectional view taken in the plane indicated by the line 10—10 of Figure 9 and looking in the direction of the arrows, the table being shown in section;

50 Figure 11 shows in fragmentary form still another modification of the invention wherein the cushion retaining means is integral with the anchor;

55 Figure 12 is a vertical sectional view taken in the plane indicated by the line 12—12 of Figure 11, looking in the direction of the arrows, the table being in section;

Figure 13 is a fragmentary view in plan showing another aspect taken by the form of the invention of Figures 7 and 8 wherein the yielding material extends beyond the retaining member;

60 Figure 14 is a sectional view taken in the plane indicated by the line 14—14 of Figure 13 and

looking in the direction of the arrows, the table being in section; and

Figure 15 shows, in plan, still another modification of the invention, wherein the cushioning member is of yielding metallic material.

The drafting machine anchor illustrated in Figures 1 through 6 has in principle substantially the form of that shown in the C. W. Keuffel Patent No. 2,266,765, dated December 23, 1941, and comprises an elongated housing 5 having a plane surface 9 for engagement with the remote side 11 of a drafting table. The housing 5 is shown as elongated and provided at each end with a bracket 13 in which is rotatably mounted a clamping screw 15 of any desired or common shape adapted to engage the under side of the drafting table. Above the housing 5 and intermediate the brackets 13, is shown a portion 19 adapted to rest upon the table 10 and with the clamping screws 15 clamp the anchor to the table. Obviously, however, any convenient form of anchor may be utilized with the device of this invention so long as there extends a portion 19 of any shape above the surface of the table. As illustrated the portion 19 is relatively narrow in the transverse direction of the table and relatively longer in the direction of vertical lines drawn on the table.

The portion 19 must, obviously, be formed of metal to afford the necessary strength and rigidity. Such hard material, if engaged by the straight-edges, often damages the edges so that straight lines cannot be drawn therewith. It is proposed, therefore, to cushion the anchor member 19 and provide a yielding non-metallic surface, in the embodiment of this figure, which, if engaged by the straight-edges, will result in no damage thereto. To this end, a guard member is provided which, preferably, is formed of yielding non-metallic material, such as rubber, preferably having a high degree of resiliency and elasticity. The guard member is conveniently removable and comprises the side walls 23 and forward end wall 25, all depending from a top wall 27 so that the guard member may be slipped over the anchor portion 19 and substantially cover all exposed surfaces thereof.

Preferably, in order to retain the cushioning device 23-27 in position, the bottom edges of the side walls 23 may be connected by a transversely extending strip of yielding or elastic material 29 (Figure 6) which will give when the cushioning member is forced on the member 19 but which, when in position thereon, will hold the cushioning member in position by virtue of its elasticity. In the illustrated embodiment, the member 19 is formed with a transversely extending recessed portion 31 to receive the strap 29 and prevent its displacement and thereby prevent the accidental removal of the cushioning member from the anchor portion 19. Thus no drawing tool, such as a straight-edge, can come into contact with the exposed metallic portion of the anchor, since in every position it will contact some portion of the cushioning wall 23,25.

If desired, rearwardly or adjacent the pivot of the drafting machine arm, the wall of the cushioning member may be enlarged or thickened, as at 35, to provide a bumper portion to intercept a straight-edge and prevent it from contacting with any metallic housing portion 39 for the pivot of the counterbalancing means. If desired, a curved rib 36 also of non-metallic material may be formed on the upper surface of the inner ex-

tremity of the sleeve and so shaped as to conform to the shape of the anchor at that point.

A cushioning member of the character described serves conveniently as a resting place for the head of the drafting machine when not in use, particularly in those situations where the drafting board is inclined and it is desired to hold the head out of the way when not in use to relieve the load on counterbalancing devices. To this end, the front edge 25 of the cushioning device may be provided with a bead 33 to serve as a stop behind which the head may be disposed, the bead 33 functioning to prevent the head from slipping off the anchor.

A modification of the invention is illustrated in Figures 7 and 8. Here the anchor portion resting on the table is shown as taking the form of a generally rectangular portion 40 to which the articulated arm, indicated in broken lines at 41, is pivoted as at 42. Such anchor member 40 is secured to the table in any convenient manner as by a depending clamp supporting member 43 extending around the table. A cushioning device, such as of yielding non-metallic material, for instance rubber, in the form of a three-sided frame comprised of the side portions 44, 46 and a front end portion 48 may surround the anchor member 40 in close proximity but, as illustrated, in spaced relation thereto. Conveniently, the yielding non-metallic material is retained in position by a metallic frame comprised of a plate portion 50 preferably of slightly larger area than the anchor member and adapted to be disposed beneath the anchor portion 40 and held in place thereby and an upwardly extending wall portion 52 extending along the three adjacent edges of plate 50 so as to be disposed in spaced relation to the anchor portion 40. The vertical wall portion is conveniently formed with an overlying portion 54 extending in a horizontal plane away from the anchor portion on all three sides thereof above the table to retain therebelow the yielding non-metallic cushioning frame 48. As shown, the outer face of the non-metallic material is flush with the edge of the frame portion 54. In Figures 13 and 14, a somewhat similar construction is shown in which like parts are given similar reference characters. However, in this form of the invention, the rubber cushion 43 extends beyond the retaining plate 41 and the exposed corners 45 are rounded. Thus, as illustrated in Figure 7, the straight-edge 56, whether it is in the position generally indicated by the broken line position at A or B or C, cannot contact with the metal of the anchor 40 but is shielded therefrom and cushioned by the rectangular strip of yielding or non-metallic cushion.

A modified form of the invention illustrated in Figures 7 and 8 is illustrated in Figures 9 and 10 wherein a three-sided strip of yielding non-metallic material 60 is retained against displacement surrounding the anchor 40. This three-sided strip 60 is illustrated as rectangular in cross-section and is held in place by a metallic frame consisting of a horizontal portion 62 and a portion 64 depending from the inside edge of the portion 62 and of a height materially less than the thickness of the rectangular strip of material 60. Such a strip is held in position by means, say, of screws 66 passing through apertures in the frame member 62 and through the yielding non-metallic material 60 and into the wood of the drafting table 10. Thus, while held in position by a metallic frame, only yielding non-metallic material is exposed on the periphery.

of the anchor 40 for engagement by straight-edges.

Another form taken by the invention is illustrated in Figures 11 and 12 wherein a vertical peripheral flange 70 is formed integral with the anchor portion 72 which rests upon the table 10 and is positioned by the anchor portion 43. At the upper portion of the peripheral flange 70 there is an integral horizontal rim 74 extending outwardly on the three sides of the anchor portion 70 over the drafting table. A strip of yielding non-metallic material 76 is disposed within the space defined by the wall 70 and the rim 74 and retained therebetween on the table to cushion engagement of a straight-edge if brought in contact therewith. If desired, the yielding non-metallic material strip 76 of Figures 11 and 12 may extend considerably beyond the flange 74 as has been explained in respect of the modifications illustrated in Figures 13 and 14, thus affording relatively more yielding material extending beyond the limit of the flange 76, to avoid any contact of any part of the head with the anchor.

While the various cushions hereinbefore described have been illustrated in Figures 7 through 14 as rectangular in cross-section, it will be obvious that the cushions may assume varying shapes, such as cylindrical or tubular and still be capable of being held in position in the manner illustrated. Furthermore, while the cushion has been specifically described as rubber, which may of course also be sponge rubber, felt, synthetic sponge-like material or other non-metallic material may be used even though not yielding or resilient to the degree of rubber, as, for instance, pith, just so long as its composition will not be hard enough to mar or break the straight-edges on impact.

There are many drafting machine anchors in use which differ in size and shape, but in every situation it is desirable to prevent contact of the straight-edges with the hard material of the anchor. In addition to the foregoing instrumentalities which can be availed of to afford a buffer or bumper for the straight edges, a further modification is shown in Figure 15. An anchor portion overlying the edge of a table 10 is illustrated generally in broken lines and identified by the reference character 80. A yielding or resilient metallic member, such as a leaf spring 82 is preferably of a length greater than the width of the member 80 and is coiled at its ends, as at 84. The looped extremities 85 are secured, as by screws 86, to the table 10 in such position that the yielding or spring-like metallic member 82 is disposed in spaced relation to the anchor 80. Such a spring can be of very light and flexible material. While not soft, as rubber can be, it is nevertheless yielding upon impact of a straight-edge. If a straight-edge touches either the portion 82 or the central portion 88, the spring will yield and serve as a cushion preventing contact of the straight-edge with the anchor 80. The inherent resiliency and yielding characteristics of the spring will not abrade or otherwise damage a straight-edge coming in contact therewith.

It will thus be seen that devices are provided which may be interposed between the straight-edges of a drafting machine and the anchor thereof to yield and therefore cushion impact of the straight-edges and prevent contact with the relatively hard surface of the anchor and consequent damage to the edges. Such cushioning devices may be of yielding non-metallic material or of yielding metallic material, preferably resilient

or elastic. They may be either permanently mounted with respect to the anchor either on the anchor or on the drafting table. Moreover, they may be removably mounted on the anchor as a U-shaped member telescoped thereover, or mounted on the drafting table. Moreover, such devices may, in effect, be interchangeable so that the same device is applicable to anchors of various shapes and forms.

10. Various modifications will occur to those skilled in the art in the composition, configuration and disposition of the component elements going to make up the invention as a whole as well as in the situation in which the same is used, and no limitation is intended by the phraseology of the foregoing specification or illustrations in the accompanying drawings except as indicated in the appended claims.

What is claimed is:

20. 1. In a device of the character described, the combination with a drafting machine comprising means adapted to be anchored to a drafting table and a straight-edge movable over the drafting table, of cushioning means and means proximate the anchored means to retain the cushioning means interposed between the anchored means and the straight-edge means.

25. 2. In a device of the character described, the combination with a drafting machine comprising means adapted to be anchored to a drafting table and a straight-edge movable over the drafting table, of cushioning means and means carried by the anchored means to secure the cushioning means between the anchored means and the straight-edge means in the plane of movement of the straight-edge means.

30. 3. In a device of the character described, the combination with a drafting machine comprising means adapted to be anchored to a drafting table and a straight-edge movable over the drafting table, of cushioning means and means to secure the cushioning means to the surface of the drafting table proximate the anchored means in the path of movement of the straight-edge means.

35. 4. In a device of the character described, the combination with a drafting machine comprising means adapted to be anchored to a drafting table and a straight-edge movable over the drafting table, of cushioning means comprising yielding non-metallic material and means to position the cushioning means proximate the anchored means in the path of movement of the straight-edge means.

40. 5. In a device of the character described, the combination with a drafting machine comprising means adapted to be anchored to a drafting table and a straight-edge movable over the drafting table, of cushioning means comprising yielding material and means to position the cushioning means proximate the anchored means in the path of movement of the straight-edge means.

45. 6. In a device of the character described, the combination with a drafting machine comprising means adapted to be anchored to a drafting table and a straight-edge movable over the drafting table, of cushioning means and means to retain the cushioning means proximate the anchored means and in the path of movement of the straight-edge.

50. 7. In a device of the character described, the combination with a drafting machine comprising means adapted to be anchored to a drafting table and a straight-edge movable over the drafting table, of cushioning means comprising resilient metallic material proximate the anchored means

and interposed between the anchored means and the straight-edge means.

8. In a device of the character described, the combination with a drafting machine comprising means adapted to be anchored to a drafting table and a straight-edge movable over the drafting table, of cushioning means proximate the anchored means and interposed between the anchored means and the straight-edge, a frame to position the cushioning means and means to secure the frame to the table.

9. In a device of the character described, the combination with a drafting machine comprising means adapted to be anchored to a drafting table and a straight-edge movable over the drafting table, of cushioning means proximate the anchored means and interposed between the anchored means and the straight-edge, and a frame integral with the anchoring means to position the cushioning means.

10. In a device of the character described, the combination with a drafting machine comprising means adapted to be anchored to a drafting table and a straight-edge movable over the drafting table, of cushioning means and a frame having means interposed between the anchored means and the drafting table to retain the cushioning means in position in the path of movement of the straight-edge.

11. In a device of the character described, the combination with a drafting machine comprising means adapted to be anchored to a drafting table and a straight-edge movable over the drafting table, of cushioning means comprising a leaf spring of resilient metallic material proximate the anchored means and in the path of movement of the straight-edge, said leaf spring having coiled ends and a screw passing through each coiled end and entering the table to secure the spring in place.

12. In a device of the character described, the combination with a drafting machine comprising anchoring means adapted to extend over a drafting table and a straight-edge movable over the drafting table, of generally tubular cushioning means telescoping over the anchoring means and interposed between the anchoring means and the straight-edge and in the path of movement of the straight-edge.

13. In a device of the character described, the combination with a drafting machine comprising an elongated plate-like member adapted to be anchored to the surface of a drafting table and a straight-edge movable over the drafting table, of cushioning means comprising yielding non-metallic material adapted to embrace three sides and overlie the top of the anchored member and an elastic strip extending between the sides beneath the anchored means to retain the cushioning means in position.

14. In a device of the character described, the combination with a drafting machine having a straight-edge and comprising means overlying a drafting table and adapted to be anchored thereto, and a straight-edge movable over the drafting table, of cushioning means comprising a peripheral wall, U-shaped in plan and having a top member and a bottom member and adapted to telescope over the overlying means.

15. In a device of the character described, the combination with a drafting machine having a straight-edge and comprising means overlying a drafting table and adapted to be anchored

thereto, and a straight-edge movable over the drafting table, of cushioning means of yielding non-metallic material comprising an end wall and side walls and a covering surface member carried by the walls and adapted to fit over the anchored means and interposed between the anchored means and the straight-edge, said cushioning means being provided with a transversely extending strap having elastic characteristics between the bottom edges of the side walls.

16. In a device of the character described, the combination with a drafting machine having a straight-edge and comprising means overlying a drafting table and adapted to be anchored thereto, and a straight-edge movable over the drafting table, of cushioning means of yielding non-metallic material comprising an end wall and side walls and a covering surface member carried by the walls and adapted to fit over the anchored means and interposed between the anchored means and the straight-edge, said cushioning means being provided with a transversely extending strap having elastic characteristics between the bottom edges of the side walls and a bead on the upper surface of the cushioning means proximate the end thereof as a stop to prevent displacement of an element of the drafting machine placed on the cushioning means.

17. As an article of manufacture, cushioning means for the anchor of a drafting machine having a straight-edge movable over the drafting table, comprising cushioning means telescoped over the anchor in the path of movement of the straight-edge.

18. As an article of manufacture, cushioning means for the anchor portion of a drafting machine overlying the drafting table and having a straight-edge movable over the drafting table, comprising cushioning means of yielding non-metallic material carried by the anchored means and in the path of movement of the straight-edge.

19. In a device of the character described, the combination with a drafting machine comprising means adapted to be anchored to a drafting table and a straight-edge movable over the drafting table, of cushioning means comprising a leaf spring of resilient metallic material proximate the anchored means and in the path of movement of the straight-edge and means to secure the spring in place.

20. In a device of the character described, the combination with a drafting machine having a straight-edge and comprising means overlying a drafting table and adapted to be anchored thereto, and a straight-edge movable over the drafting table, of cushioning means of yielding non-metallic material comprising an end wall and side walls and an upper surface member and adapted to fit over the anchored means.

21. In a device of the character described, the combination with a drafting machine having means to anchor the drafting machine to a drafting table and straight-edge means movable over the drafting table, said anchoring means comprising frame means adapted to be disposed on the upper side of the table and cushioning means at least on sides of the frame means in the path of movement of the straight-edge means.

ARVID HEIRETH.
